[57] **CLAIM**

The ornamental design for a combined bottle and squeegee package, as shown.

DESCRIPTION

FIG. 1 is an elevational view of a combined bottle and squeegee package showing my new design;

FIG. 2 is an elevational view looking from the right of FIG. 1;

FIG. 3 is an elevational view looking from the left of FIG. 1;

FIG. 4 is a top plan view;

FIG. 5 is a bottom plan view;

FIG. 6 is a view similar to FIG. 1 with the squeegee placed under the cap and with the cap cover in open position;

FIG. 7 is a top plan view thereof; and

FIG. 8 is a sectional view taken along line 8—8 of FIG. 6.
